UNITED STATES PATENT OFFICE.

THOMAS ALFRED MOUNTFORD, OF NEWARK, NEW JERSEY.

SAFETY DEVICE FOR PUNCH-PRESSES.

1,282,452.

Specification of Letters Patent. Patented Oct. 22, 1918.

Application filed July 29, 1912, Serial No. 711,976. Renewed March 28, 1918. Serial No. 225,349.

To all whom it may concern:

Be it known that I, THOMAS ALFRED MOUNTFORD, a subject of the King of Great Britain, residing at No. 162 Seymour avenue, city of Newark, county of Essex, and State of New Jersey, have invented certain new and useful Improvements in Safety Devices for Punch-Presses and the like; and I do hereby declare the following to be a full, clear, and exact description of the invention, such as will enable others skilled in the art to which it appertains to make and use the same.

My present invention relates to devices for preventing injury to operatives of power presses and the like and consists in the main in providing a guard which must be placed in an effective position relative to the punch and die of the press before the clutch of the press can be released and the punch operated and which guard is so designed and mounted that it cannot assume its effective position if the hands or fingers of the operative are in dangerous proximity to the punch and die, and therefore, the press cannot then be operated. The invention further consists in operating the guard to its effective position by an initial movement of the controlling member of the press, such for instance, as the treadle, which initial movement must be completed before a continued movement of the controlling member releases the clutch, and which continued movement and release of the clutch is prevented if the guard is prevented from assuming its effective position by the presence in its path of the operative's finger or hand; and it is intended that the leverage exerted upon the controlling member by the presence of the operative's hand or finger in the path of the guard shall be sufficient to stop the movement of the controlling member without injury to the operative's hand or finger. An organization of a power press and guard embodying these provisions is illustrated in the accompanying drawings, in which

Figure 1 is a side elevation;

Fig. 2, a front elevation, and

Figs. 3 and 4, details in side elevation of the guard and controlling member in two positions.

Referring to the drawings, a power press having the usual frame A, crank shaft B, plunger C, and fly-wheel D, is shown provided with a die E and punch F. The crank shaft B is adapted to be released and thrown

into connection with the fly-wheel D by a clutch G which may operate in any of the well known ways. The clutch G is operated by a downward pull on a rod H which is normally held in its upper position by the spring I which likewise holds the clutch G out of engagement with the fly-wheel.

A guard J is pivoted to oscillate with a shaft K from an upper or ineffective position in which it appears in Figs. 1 and 2 to a lower or effective position in which it appears in Fig. 4. A spring L coiled on the shaft K normally keeps the guard in its upper position and the engagement of a lever M, which is really the controlling member of the press, with a cam N on shaft K throws the guard to its lower position. The nose O of the lever M contacts a projection P at a point not far from the axis of the shaft K while that portion of the guard J which will hit the fingers or hand of the operative should they project into the danger zone is considerably removed from the axis of shaft K and therefore but slight resistance offered by the guard to the finger will, owing to the leverage prevent a continuation of the movement of the lever M even though considerable pressure be brought to bear by the foot upon a treadle Q connected by a rod R with the lever M. This arrangement effectually prevents the full operation of the lever M when a finger is in the danger zone and does so without injury to the finger by a hard pressure of the guard.

The nose O of the lever M after moving the guard to its lowermost or effective position is allowed to pass the projection P on the cam N and continue its motion. During this continued movement of the lever M, after the guard has been carried to its safety position, the clutch G is to be operated. A spring S normally holds the lever M and the treadle Q in their upper positions. The lever M is connected with the clutch operating rod H by a connecting rod T through engaging terminal loop portions, as shown in Figs. 1 and 2, to provide enough lost motion to require the movement of lever M through an angle sufficient to complete the operation of the guard J before a pull is brought to bear on the clutch operating rod H. It will therefore, be seen that the controlling member of the press which is shown in the lever M, must complete the movement of the guard to its effective position before it can release the clutch.

I have shown the guard J as a rod which sweeps through the danger zone and has a cage which surrounds the danger zone when the effective position is reached, but it is obvious that the rod alone may be used without the cage.

Having thus described my invention what I claim is:

1. In a safety device for punch presses and the like, in combination, a guard movable to an effective position, a controlling member therefor, means connected to said guard and normally in the path of said controlling member whereby movement of the controlling member will cause said guard to occupy its effective position; said means moving out of the path of said controlling member when the guard occupies its effective position to permit further movement of the controlling member, means for actuating said controlling member, a clutch, and clutch controlling means actuated by said controlling member only upon the further movement thereof.
2. In a safety device for punch presses and the like, in combination, a frame, a shaft rotatably supported thereon and carrying a guard, a controlling member movably supported on said frame, said shaft being provided with means normally in the path of said controlling member whereby movement of said member will rotate said shaft to cause said guard to occupy its effective po-

sition, said means moving out of the path of said controlling member when said guard occupies its effective normal position to permit further movement of said controlling member, means for actuating said controlling member, a clutch, and clutch controlling means actuated by said controlling member only upon the further movement thereof.

3. In a safety device for punch presses and the like, in combination, a frame, a shaft rotatably supported thereon, a cam secured to said shaft and provided with a projection, a lever having one end pivotally supported upon said frame and having a nose at its other end adapted to engage the projection on said cam, whereby movement of said lever will rotate said shaft to cause said guard to occupy its effective position, the projection on said cam moving out of engagement with the nose on said lever when said guard occupies its effective position to permit further movement of said lever, a clutch, and clutch controlling means actuated by said lever only upon the further movement thereof.

In testimony whereof I affix my signature, in presence of two witnesses.

THOMAS ALFRED MOUNTFORD.

MARCUS C. HOPKINS,
M. A. BILL.

Correction in Letters Patent No. 1,282,452.

It is hereby certified that in Letters Patent No. 1,282,452, granted October 22, 1918, upon the application of Thomas Alfred Mountford, of Newark, New Jersey, for an improvement in "Safety Devices for Punch-Presses," an error appears in the printed specification requiring correction as follows: Page 2, line 36, claim 2, strike out the word "normal;" and that the said Letters Patent should be read with this correction therein that the same may conform to the record of the case in the Patent Office.

Signed and sealed this 26th day of November, A. D., 1918.

[SEAL.]

R. F. WHITEHEAD,
Acting Commissioner of Patents.
